UNITED STATES PATENT OFFICE.

CLARK A. SIGAFOOS, OF OMAHA, NEBRASKA.

JOGGER FOR PAPER-FOLDING MACHINES.

1,120,983.

Specification of Letters Patent. Patented Dec. 15, 1914.

Application filed June 22, 1912. Serial No. 705,322.

To all whom it may concern:

Be it known that I, CLARK A. SIGAFOOS, a citizen of the United States and a resident of Omaha, in the county of Douglas and 5 State of Nebraska, have invented certain new and useful Improvements in Joggers for Paper-Folding Machines, of which the following is a specification.

My invention relates to paper folding machines and more particularly to the devices 10 known as "joggers" or paper straighteners for such machines.

It is the object of my invention to provide a paper straightening and gaging device of 15 simple and inexpensive construction, which may be quickly and easily adjusted to different positions so as to accommodate sheets of varying sizes, and having a special form of driving connection by which the straightener mechanism is actuated at any of its 20 adjusted positions without adjustment of said driving connection.

In the accompanying drawings Figure 1 is a plan view of a mechanism embodying 25 my invention, Fig. 2 is a transverse vertical sectional view taken on the plane of the line $x-x$ of Fig. 1, and Fig. 3 is a longitudinal vertical sectional view taken on the plane of the line $y-y$ of Fig. 1.

There is shown in the drawings only those 30 parts of the folding machine with which the straightening and gaging devices are connected and with which they directly co-operate. The said parts are the frame-members 1 and 2, the carrier-belts or tapes 3, a driving roller 4 and a driving shaft 5. The general arrangement and functions of 35 these parts will be apparent. The tapes or carrier-belts 3 are those on which the paper is received when first delivered to the folding machine, and they move continuously in the directions indicated, at one end passing around a roller 6 and at the other end passing around small individual pulleys 7 as indicated in Fig. 3. On the frame-members 1 and 2, respectively, are secured 40 standards 8 and 9, and upon the latter standard is revolvably mounted a small pulley 10. A transverse endless belt 11 passes around 45 the driving roller 4, thence the upper and lower portions of said belt are reversed by crossing them, and they then pass around

the pulley 10, across the machine between the upper and lower portions of the carrier-belts, and around a pulley 12 disposed in 55 horizontal alinement with the pulley 10, so that the upper portion of the transverse belt lies just beneath and in contact with the upper portions of the carrier-belts. The pulley 12 is journaled on a lever 13 which 60 is pivotally connected with the standard 8. Through the upper end of the lever 13 is passed a small adjusting screw 14 of which the end may be screwed in against the standard so as to push the lever outwardly and 65 tighten the transverse belt.

In the upper parts of the standards 8 and 9 are carried the parallel transverse rods 15 and 16, the same being disposed slightly below the upper portion of the transverse 70 belt 11, the rod 15 being behind the said belt and the rod 16 being in front of the belt when viewed as in Fig. 1. The ends of the rod 15 are fixedly secured in the standards, and the rod 16 is revolvable therein, the portion of said rod between the standards being threaded. The outer end portion of the rod 16 has a pin 17 passing through it, said pin being adapted for engagement with a notch formed in the tubular hub-portion of 75 a crank 18 which is removably disposed on the end of the rod for the purpose of enabling it to be readily turned. The inner end portion of the rod 16 is reduced in size and, after passing through the standard 9, has 80 a coil spring 19 placed around it, the one end of the spring bearing against the face of the standard and the other end pressing against a washer held on the end of the rod by a pin 20. On the central portions of the 85 rods 15 and 16 is supported the plate 21, the same being slidable on the rod 15, and being movable transversely along the rods by turning the threaded rod 16 which is screwed through it. Along the outer edge of the 90 plate is an upwardly extending guide-flange 22 of which the ends are curved outwardly, as shown in Fig. 1. The upper surface of the plate is so disposed as to be in contact with the carrier-belts which pass over it, 100 and in said upper side of the plate is a transverse groove through which the belt 11 passes, as shown in Figs. 2 and 3. A notch is formed in the guide-flange 22 coincident

with the groove in the plate, and at the sides of said notch are outwardly extending lugs 23 between which is pivotally mounted the roller-arm 24. Said arm extends inwardly from the pivot-pin, its inner end is turned upwardly and forked, and between the forked ends is revolvably mounted the roller 25. To the middle part of the roller-arm is secured the end of an arm 26 which passes up and over one of the lugs 23, and then downwardly to a point below the plate 21. To the lower end of the arm 26 is secured one end of a cord or flexible connecting member 27, which passes inwardly from the arm and around a small pulley carried on the end of a lever 28, thence outwardly and around a pulley 29 mounted on the standard 8, and thence extends inwardly and has its other end connected with the outer edge of the plate 21. The lever 28 is fulcrumed on a lug extending out from the side of the frame-member 2 and its lower end lies adjacent to a cam 30 carried on the driving shaft 5. On said end of the lever 28 is a roller 31 which is held in engagement with the cam by means of a spring 32, connected with the lever and the frame, as shown. When the flexible connecting member 27 is not placed in tension by movement of the lever 28 the weight of the roller 25 causes it to drop into engagement with the transverse belt 11, or, if a sheet of paper is being conveyed over the plate 21 by the carrier-belts, to press said paper down into engagement with the transverse belt. When the flexible connection is placed in tension by movement of the lever 28 the roller-arm is swung upwardly, and paper carried by the belts 3 can pass freely under it.

In the operation of the mechanism the belts 3 and the transverse belt 11 are each moved continuously in the directions indicated in the drawings. The plate 21 is adjusted transversely by turning the threaded rod 16, so that the inner side of the guide-flange 22 is at the position to which it is desired to gage the edges of the sheets of paper being conveyed by the belts 3. The lever 28 is actuated intermittently by the cam 30 so that the flexible connection 27 is alternately placed in tension and the tension relaxed. When the tension on the member 27 is relaxed and the roller 25 thereby permitted to drop down, the paper is pressed against the belt 11 and moved transversely thereby until its outer edge is brought into engagement with the guide-flange 22. The parts are so proportioned that after the edge of the paper is brought to engagement with the guide-flange the tendency of the belt 11 to move it farther will be insufficient to cause the paper to wrinkle or bulge upwardly. Should the paper tend to bulge upward between the roller and guide-flange, it is held

down by the portion of the roller-arm adjoining the forked end thereof.

It should be especially noted with reference to the flexible connection for actuating the roller-arm, that by the peculiar arrangement of the cord 27, when the position of the plate 21 is changed the driving connection is also changed automatically and the timing of the movement of the roller-arm is not changed. Thus, if the plate be moved either inwardly or outwardly, the ends of the cord attached to the plate and to the arm 26 are both moved in the same direction and the cord passes around the pulleys on the lever 28 and standard 8 to permit the movement. By this means the operator is enabled to change the position of the gage and straightener even while the machine is running, the crank 18 being turned with one hand while the other hand is used to lift the upper portions of the belts 3 over the roller 25, roller-arm, guide-flange and the lugs 23, when the transverse movement given to the plate is such that the said parts must move past any of the carrier-belts.

Now, having described my invention, what I claim and desire to secure by Letters Patent is:

1. In a device of the class described, the combination with carrier-belts, of a stationary frame, a gage, means for adjusting the position of the gage transversely of the carrier-belts, conveying means for moving paper transversely of the carrier-belts toward the gage, a pressing device carried on the gage and adapted to engage paper on the carrier-belts to hold the same against said conveying means, an intermittently-moving actuating-lever for said pressing device, and a unitary flexible element slidably engaging the frame and connecting the actuating-lever and pressing device so as to transmit the movements of the former to the latter when the gage is in any position.

2. In a device of the class described, the combination with carrier-belts, of a frame, a belt extending transversely to the carrier-belts, a gage holding means movably connected with the gage for holding paper in engagement with the transverse belt, means for moving the gage and holding means transversely to the carrier-belts, an actuating lever for the holding means, and a flexible member having one of its ends connected with the holding means, its other end connected with the gage, and its intermediate parts slidably connected with the actuating lever and the frame, for the purpose set forth.

3. In a paper folding machine, paper carrying devices, a frame, a jogger mechanism for moving paper transversely to the carrying devices, means for varying the position of the jogger mechanism transversely to the

carrying devices, an actuating lever for the jogger mechanism, and a flexible member having one of its ends connected with a fixed part of the jogger mechanism, its other end 5 connected with a movable part of the jogger mechanism and its intermediate parts slidably connected with the lever and the frame.

In testimony whereof I have hereunto subscribed my name in the presence of two witnesses.

CLARK A. SIGAFOOS.
